Term of patent 14 years

(Cl. D34—15)

FIGURE 1 is a front elevational view of the toy cap device in open position with the handle swung out vertically to form the grip and the barrel swung out horizontally to represent a gun;

FIGURE 6 is a front elevational view of the toy cap gun device in closed position wherein it is disguised as a pocket knife by having the barrel representation folded in and the extending grip turned back into the handle, having its blade closed;

We claim:

The ornamental design for a disguised toy cap gun, as shown and described.
